INDOOR TELEVISION ANTENNA

Marvin P. Middlemark, Rego Park, N.Y.
(47-39 49th St., Woodside 77, N.Y.)

Filed Aug. 29, 1962, Ser. No. 71,486

Term of patent 14 years

(Cl. D26—14)

FIGURE 1 is a front perspective view of an indoor television antenna showing my new design;

FIGURE 2 is a front elevational view thereof; and

FIGURE 3 is a side elevational view thereof.

The dominant portions of my design reside in those portions shown in full lines. In the drawing, the broken away extensible rod is symmetrical with its opposing rod.

I claim:

The ornamental design for an indoor television antenna, as shown and described.
